UNITED STATES PATENT OFFICE.

WILLIAM S. PATTERSON, OF HOMESTEAD, PENNSYLVANIA.

DESIGN FOR A RAIL-SPLICER.

SPECIFICATION forming part of Design No. 26,404, dated December 15, 1896.

Application filed October 13, 1896. Serial No. 608,784. Term of patent 14 years.

To all whom it may concern:

Be it known that I, WILLIAM S. PATTERSON, a citizen of the United States of America, residing at Homestead, in the county of Allegheny and State of Pennsylvania, have invented a certain new and useful Design in Rail-Splices, of which the following is a specification, reference being had therein to the accompanying drawing.

This invention relates to certain new and novel designs in rail-splices, and in describing the invention in detail reference is had to the accompanying drawing, forming a part of this specification, and wherein like letters of reference indicate similar parts throughout the view, which is a perspective view of my design.

The principal feature of my design is the tread *a*, conforming to the tread of the rails, the vertical sides or plates *b b*, extending outwardly at the base in flanges *c c* and terminating in flanges *d d*, the flanges *c c* being provided with apertures *e e*. 20

Having fully described my invention, what I claim is—

The design for a rail-splice as herein shown and described. 25

In testimony whereof I affix my signature in presence of two witnesses.

WILLIAM S. PATTERSON.

Witnesses:

H. M. WILSON,
H. E. SEIBERT.
